John B. Poague and William A. Poague of Virginia
Inventors

The Schedule referred to in these Letters Patent and making part of the same containing, a description in the words of the said John B. Poague and William A. Poague themselves of their improvement in the machine for rubbing, Cloves, etc.

Be it known that we John B. and William A. Poague residing near Lexington in the County of Rockbridge and State of Virginia, have made a new and useful improvement in the machine for rubbing out clover seeds which is described as follows, reference being had to the annexed drawing of the same, making part of this specification. This machine consists of a suitable frame A, in the centre of which is a spindle B, turning in a slip C on a bridge-tree D, its upper end turning in a top in a recessed trial top having a pulley E fixed on its arbor which a band passes by which it is driven, and on this spindle is secured a conical shaped stone runner G, turning with in a corresponding inverted conical stone bed H. The runner and bed are dressed or prepared obliquely in the manner represented in the drawing. One or two feeders I, are secured to the upper end of the spindle for feeding the machine to the stone. This is placed over the bed in to which the clover seeds are put. An inclined board J, is placed below the runner on which the seed and chaff are received and conveyed to a common pan which may be placed in front, or under the machine, for separating the seed from the chaff. Operations. The heads of clover after being threshed from the stems, are put into the machine, from whence they descend to between the bed and runner. The feeders stirring and forcing them into the throat of the machine. The seed is rubbed from the hulls by the rotary motion of the runner. The stationary feed, the projections on the inside of the tree, partially arresting the hulls whilst the projecting on the runner rub out the seed from them. The whole then falls on the inclined board below, the seed being separated from the chaff by a pan in the usual manner as before mentioned. The gearing may consist of a cog wheel and pinion. This we claim as an invention and which we desire to secure by Letters Patent in the before described machine for rubbing out clover seeds.
